DRAWING MECHANISM FOR TEXTILE MACHINES

Ramon Balmes Solanas, Santa Coloma de Cervello, Spain, assignor to Estirajes Balmes, S. A., Barcelona, Spain

Application August 2, 1954, Serial No. 447,187

Claims priority, application Spain August 31, 1953

2 Claims. (Cl. 19—130)

This invention relates to an improvement in or modification of the drawing mechanism claimed in my prior specification Ser. No. 384,245, filed October 5, 1953, which describes mechanisms for drawing textile rovings or slivers, employed both in spinning machines and in preparation machines, in which the roving or slivers of fibres passes through between a series of pairs of rollers in succession, and sometimes through other members, which rotate with the fibres.

For the purpose of enabling a high draft of the roving to be effected, it is the practice in these mechanisms to guide the fibres to the final or delivery rollers by means of members that move with and grip the fibres, preventing the fibres from becoming detached from the roving, but permitting them to move relative to the gripping members in order that the drawing may be effected.

In my said prior specification there is employed, for guiding the fibres to the drawing rollers, a small device which is interposed between two consecutive pairs of rollers, and which acts as a conductor and presser of the fibres, and at the same time as a uniter of these fibres or a condenser of the roving. This device is constituted by a rigid frame, which carries a pressing roller for the fibres, which bears upon the lower rollers of the two consecutive pairs of rollers of the drawing mechanism. The frame moreover comprises in its lower portion a condenser of the roving and in its upper portion a handle to facilitate the operation of placing the device in the machine and withdrawing it therefrom. The roving in passing bears against the lower part of the pressing roller, and passes through the condenser which unites the fibres and gives them cohesion. In one form of construction described in the said prior specification the pressing roller is slotted along its centre line, forming an annular groove into which the roving is introduced, and which acts as a condenser of the fibres, and the frame is open through the lower part, forming an outlet mouth which becomes progressively narrower so as to guide the roving to the groove of the roller.

The present invention relates to an improvement in or modification of this form of construction described in the abovementioned specification which is particularly applicable to long fibres, and it consists essentially in replacing the grooved cylinder by two short cylinders or thick discs arranged co-axially and close to one another, which bear upon the lower rollers of the drawing mechanism and revolve by contact with them, the roving being passed through between the contiguous faces of the two cylinders or discs, which are quite smooth. The frame forms on each side a neck or trunnion, which serves as a stationary shaft for the rotation of the corresponding cylinder, and the two cylinders bear against one another with their adjacent smooth faces.

The necessary parts of a drawing mechanism having various pairs of rollers of the type described, with the improvements forming the subject of this invention, are illustrated in the accompanying drawings, in which

2

Figure 1 represents diagrammatically in transverse section two adjacent pairs of rollers of the drawing mechanism, between which is arranged the device that drives the rovings;

5 Figure 2 is a front view of this driving device, with some parts in section;

Figure 3 is a side view, looking from the righthand side of Figure 2; and

10 Figure 4 indicates the construction of the device, its various parts being represented separated from one another.

According to this invention there is applied to the drawing mechanism a device for advancing and uniting the roving, consisting of a frame, which as a whole is denoted in the drawings by the numeral 1, and in the interior of which are mounted two discs or short cylinders 2 and 3, arranged in axial alignment with one another, and in such a way that they are very close to one another at two contiguous end faces, leaving only just a small clearance.

15 Each of the discs or cylinders 2 and 3 has on its outer face a circular recess 4, in which fits a neck or flange 5 provided on the inner face of the frame and serving to support the disc or cylinder, permitting it to revolve loosely in full freedom. The other side of each disc is close to the opposite disc, and in this way, although there are two independent discs or cylinders, they remain conveniently supported so as to be able to revolve with complete freedom while remaining co-axial.

20 Figure 1 consists of two symmetrical parts 11 and 12, each of which forms half the frame, and which are united to one another by means of a screw 13 located in the upper portion. In the central portion each of these parts is formed with the aforementioned neck or flange 5, to serve as a support for the corresponding disc or cylinder 2 or 3, and in the lower portion they each have a prolongation, the edge of which has a vertical or approximately vertical upper portion 14 and an inclined lower portion 15. Upon the two parts 11 and 12 being united, 25 these downward prolongations form a very wide entrance 16, which progressively narrows upwards, until it terminates in a vertical space 17, which is located in front of the line of separation 6 between the two discs 2 and 3.

30 Because of this arrangement of the frame when the device is located in the machine the roving penetrates by itself into the aperture 16, which leads it to the space 6 between the two cylinders 2 and 3, so that the roving remains threaded without the necessity for any special care.

35 The upper portion of the frame forms an upwardly directed handle 7, which facilitates taking hold of the device as a whole in order to place it in the machine or take it out of the latter.

40 The two parts 11 and 12 of the frame are shown in the drawing as having the necks 5 each provided with a central aperture 8 of relatively large diameter, which extends right through into the recess 4 of the associated disc. This aperture 8 is not absolutely essential, and might be omitted without any serious inconvenience, but it has the advantage of rendering it possible to withdraw easily 45 with the finger any fibrils that may have been able to work themselves between the neck 5 and the recess of the corresponding cylinder.

46 This device is placed in the spinning machine as illustrated in Figure 1, that is to say, it is interposed between two pairs of rollers 9 and 10, in such a way that the cylinders 2 and 3, which project laterally from the frame 1, rest upon the lower rollers of the two pairs. The frame 1 is supported by the cylinders 2 and 3, and by its lower portion it touches the roller of the front pair 10, thus remaining stationary in its correct position.

50 When the device has thus been placed in position in

the spinning machine, the roving, which consists preferably of fibres longer than the distance between pairs of rollers, passes, as indicated diagrammatically in Figure 1, following a substantially straight line between the tangent points of the rollers of the two pairs, and without undergoing any friction, other than with the two plane faces of the two cylinders that support as well as compress it. An advancing and condensation of the roving is thus obtained under the best conditions.

I claim:

1. In a drawing mechanism for textile rovings having two consecutive pairs of drawing rollers, means comprising a frame, two short cylinders rotatably supported in said frame coaxially with and spaced from each other having opposing end faces close to each other, said frame

adapted to fit between said pairs of rollers with the axes of said cylinders parallel to said rollers and with said cylinders supported on the lower rollers of said pairs of rollers, whereby a roving may be passed between the end faces and having a lateral pressure exerted thereon to condense the roving and unite the fibers thereof.

5 2. Means as claimed in claim 1 in which said frame has in the lower portion thereof an upwardly converging space through which said roving may be introduced between the end faces of said cylinders.
